UNITED STATES PATENT OFFICE.

SADAMA ORIOKA, OF HONOLULU, TERRITORY OF HAWAII.

CURRENT MOTOR.

Application filed May 21, 1923. Serial No. 640,455.

To all whom it may concern:

Be it known that I, SADAMA ORIOKA, a citizen of the United States, residing at Honolulu, Territory of Hawaii, have invented certain new and useful Improvements in a Current Motor, of which the following is a specification.

The present invention relates to a current motor adapted to be placed in a swift running stream of water so that power may be generated for the operation of a dynamo. The invention may be used so that its power may be converted in other ways as desired.

The principal object of the invention is to provide a motor having a simple and efficient structure which will be reliable and capable of being constructed at a relatively low cost.

Another object of the invention is to provide a motor of this nature which may be assembled easily and which may be moved to a position at which it will not operate when desired.

With the above and numerous other objects in view as will appear as the description progresses the invention resides in certain novel features of construction and in the combination and arrangement of parts as will be hereinafter more fully described and claimed.

In the drawing—

Figure 1 is a top plan view of the device embodying the invention, and

Figure 2 is an elevation thereof.

Referring to the drawing in detail it will be seen that the letter A indicates a stream of water flowing in the direction of the arrow. A plurality of brackets are suitably mounted on the bank of the stream and are arranged in two vertically aligned series. In one series of brackets 1 there is rotatably supported a post 2 and in the other series of brackets 3 there is rotatably supported a post 4. The posts 2 and 4 are of similar structure and are preferably constructed with heads 5 at their upper ends which bear on the upper brackets 1 and 3 supporting the posts in proper positions. These posts may be thus readily withdrawn from the brackets when desired. An arm 6 is detachably fixed to the post 2 and a similar arm 7 is detachably mounted on the post 4. These arms 6 and 7 normally project out into the stream and are slightly curved. A plurality of stay ropes 8 are attached to these arms so that they may be held out into

the stream in a manner which will be more clearly evident as the description progresses.

The motor proper includes a chain 9 which is trained over sprockets 10 and 11. The sprocket 10 is constructed with a shaft 12 journaled in the yoke 13 which is connected to the end of the arm 6 by links 14. The sprocket 11 is mounted on a shaft 15 journaled in yoke 16 which is attached to the arm 7 by links 17. The shaft 15 terminates beyond the yoke 16 in an eye 18. The chain 9 is provided with a plurality of paddles 19. These paddles are hingedly connected to the chain so as to swing in a 90° arc whereby they may be disposed perpendicularly to the chain or parallel thereto. When the paddles 19 are disposed parallel with the chain they all extend in the same direction provided, of course, that the chain is extended flat. In actual practice the paddles below the plane of the shafts 12 and 15 are disposed parallel with the chain while those above the plane of these shafts are disposed perpendicularly to the chain. It will thus be seen that the water flowing in the direction of the arrow will cause movement of the chain since it will engage the paddles, bring them to their perpendicular position in relation to the chain thereby tending to resist the flow of water. As a paddle approaches the yoke 13 it will be pivoted to its parallel position with the chain so as to afford a minimum amount of resistance as it is moving toward sprocket 11.

A shaft indicated generally at 20 includes a pair of telescopically associated sections 21 and 22. The section 21 telescopes into the section 22 and is rotatable therewith in any suitable manner. The section 22 is journaled in a bracket 23 supported by an arm 24 which projects from the post 4 being detachably engaged therewith by a bolt 25. The section 22 of the shaft 20 terminates adjacent the shore in a beveled gear 26 which meshes with a beveled gear 27 mounted on the lower end of a shaft 28 which is journaled in bracket 29 suitably mounted at the bank or shore. This shaft 28 terminates at its upper end in a beveled gear 30. A collar 31 is disposed immediately below the beveled gear 30 so as to rest on a journal bracket 32 supported by arm 33 projecting from one of the standards 34. These standards 34 are located on a base 35 which supports a dynamo 36 operable through a gear 37. A shaft 38 is journaled in the ends of

the standards 34 and is provided at one end with a beveled gear 39 meshing with the beveled gear 30 and at its other end in a gear 40 meshing with the gear 37.

5 It will thus be seen that when the motor is operated by the stream of water, the shaft 20 will be rotated causing rotation of shaft 38 through beveled gears 26 and 27. The 10 rotation of this shaft 38 operates the dynamo through the intermediary of gears 30 and 39, shaft 38, and gears 40 and 37. If it is desired to stop the motor it is only necessary to rotate the arms 6 and 7 in a clockwise direction, as shown in Figure 1, 15 since this will cause the rotation of the arm 24 and separate the beveled gear 26 on shaft 20 from beveled gear 27. Furthermore if it is desired to bring the motor close to shore so that it may be cleaned or repaired while 20 actually in the water these arms may be still farther rotated since the more they are rotated toward the shore the closer will be disposed the motor to the shore. It will be also noted that if the motor is moved 25 toward the shore the section 21 of shaft 20 will move out of section 22 and that this telescoping shaft or any similar extensible shaft is desirable and necessary to the efficient operation and care of the mechanism. 30 It is also desirable, of course, to bring the motor close to shore when for any reason it is to be disassembled.

The particular structure and the arrangement and combination of the elements therefrom of which I have disclosed with a certain degree of particularity may be variously arranged and constructed without departing from the scope or spirit of the invention as hereinafter claimed.

40 Having thus described my invention what I claim as new is:—

1. In combination, a water propelled motor, an extensible shaft operable by said motor, means for holding the motor out in a stream of water, said means being actuatable so that said motor may be moved toward and away from the shore of the stream, thereby extending or contracting the length of said extensible shaft.

45 2. In combination, a pair of spaced hinged arms, a current motor supported between

and by said arms, means for holding said arms projected out into a stream of water and so as to rotate said arms toward the bank of said stream whereby the motor may be moved close to said bank, and an extensible shaft operable by said motor for operating a mechanism on the shore of said stream. 55

3. In combination, a pair of arms adapted to be hinged mounted on the bank of a stream of water, a current motor supported between and by said arms in said stream of water, a shaft operable by said current motor, a second shaft of extensible type 60 65 pivoted to the first shaft.

4. In combination, a pair of arms adapted to be hinged to a bank of a stream of water, means for holding said arms out into said stream of water and moving them toward 70 said bank, a pair of yokes one attached to the end of each arm, a pair of sprockets one journaled in each yoke, a chain trained over certain sprockets, paddles hinged to said chain so as to move in a 90° arc, and means 75 for transferring the power generated by said chain to a mechanism on the bank.

5. In combination, a pair of arms adapted to be hinged to a bank of a stream of water, means for holding said arms out into said stream of water and moving them toward said bank, a pair of yokes one attached to the end of each arm, a pair of sprockets one journaled in each yoke, a chain trained over certain sprockets, paddles hinged to said 80 chain so as to move in a 90° arc, a shaft 85 extending from one of said sprockets and terminating in an eye, a second shaft including telescoping sections one of which 90 terminates in an eye engaged with the eye of the first shaft, and a bracket in which said second shaft is journaled whereby the sections of the second shaft may contract 95 when the arms are moved toward the bank of the stream.

In testimony whereof I affix my signature in presence of two witnesses.

SADAMA ORIOKA.
